CRANKSHAFT TWISTING MACHINE

Alois K. Nowak, Evanston, Ill., assignor to Clearing Machine Corporation, Chicago, Ill., a corporation of Illinois

Application January 29, 1944, Serial No. 520,215

14 Claims. (Cl. 153—78)

1
In the manufacture of crankshafts for engines, with multiple throws positioned at various degrees of angularity, it has been found expedient to first forge the shaft blank with all of the crank pins in one plane, and to thereafter twist the various blanks or throws into their correlated angularity which they must assume in the finished crankshaft.

It is one of the objects of the present invention to provide an improved machine which will operate upon the forged shaft, after a single heating, to simultaneously and properly twist the pins and accurately locate them according to the design of the shaft, and at the same time avoid distortion of the various parts.

A further object is to provide an improved twisting machine of this character, in which there is provided improved means for automatically clamping the portions of the crankshaft which are to be twisted, and also those which are not to be twisted, and improved means for actuating or rotating the twisting clamps to impart the desired shape to the shaft.

A further object is to provide improved means for opening and closing the clamps, and improved means for ejecting the shaft from the clamps after they have been opened.

A further object is to provide an improved machine of this character, embodying upper and lower twisting dies and means for opening the dies while they are in the position in which they have been moved to twist the shaft, and knockout mechanism operating automatically to remove the twisted shaft from the dies, the operation of the knockout mechanism being delayed, and responsive in its actuation to the movement of the slide, in order to free the finished work from the die by lifting it a distance less than the movement of the slide.

To the attainment of these ends and the accomplishment of other new and useful objects as will appear, the invention consists in the features of novelty in substantially the construction, combination and arrangement of the several parts, hereinafter more fully described and claimed and shown in the accompanying drawings illustrating this invention, in which

Figure 1 is a front elevation of a machine of this character, constructed in accordance with the principles of this invention.

Figure 2 is a diagrammatic illustration of the machine.

Figure 3 is a top plan view of the lower portions of the holding and twisting dies, the upper dies being removed.

Figure 4 is a front elevation of the parts shown in Figure 3.

Figure 5 is an irregular sectional view, on an enlarged scale, taken on line 5—5, Figure 1.

Figure 6 is a detail vertical sectional view, on an enlarged scale, taken on line 6—6, Figure 1.

Figure 7 is a detail front elevation of a portion of the press shown in Figure 1, with parts omitted, and showing the twister actuating mechanism in position to engage the stop, to limit its movement in one direction.

Figure 8 is a detail sectional view taken on line 8—8, Figure 7.

Figure 9 is a view similar to Figure 8, showing the parts in a different position.

Figure 10 is a detail sectional view as taken on line 10—10, Figure 1.

Figure 11 is a detail sectional view, on an enlarged scale, taken on line 11—11, Figure 1.

Figure 12 is a detail sectional view, on an enlarged scale, taken on line 12—12, Figure 1.

Fig. 13 is a detail sectional view, on an enlarged scale, taken on line 13—13, Fig. 1.

Fig. 14 is an enlarged detail sectional view taken on line 14—14, Fig. 1.

Fig. 15 is an enlarged detail sectional view through one of the twister members, showing the parts in the position they will assume after the crank has been twisted thereby.

Fig. 16 is a detail sectional view similar to Fig. 15, of another of the twister members.

Fig. 17 is an enlarged detail sectional view showing the ejector mechanism and some of the twisting and holding members in section.

Referring more particularly to the drawings, and in the present exemplification of this invention, the numeral 20 designates a press bed; 21, uprights rising therefrom; 22, a crown; 23, a slide movable in guides 24 on the uprights; 25, pistons connected to the slide, which pistons operate in cylinders 26. A fluid pressure supply pipe 27 discharges into the upper ends of the cylinders 26 to lower the pistons, and a fluid pressure supply pipe 28 discharges into the lower ends of the cylinders to raise the pistons, and with them the slide 23, all as well known in this particular type of press.

Mounted upon the bed of the press are stationary holding dies or members 29, any number of which may be provided, according to the size and shape of the shaft to be twisted. In the present exemplification of this invention, four of these holding dies are shown, and each consists of separable members. Two of the die members 29 (see particularly Fig. 3) are positioned to support the

two end bearing pins 30 of the crankshaft, and the other two die members 29 are positioned therebetween so as to clamp and hold intermediate portions 31 of the crankshaft. These holding members 29 are adjustably supported upon the bed by means of fastening bolts 32 operating in slots 33.

Mounted upon the slide 23 (see particularly Fig. 14) are the holding members 34, which are also adjustably supported upon the slide by means of suitable fastening bolts 35. These upper members 34 are so positioned that when the slide is lowered, they will engage the co-operating members 29 to constitute the holding means for holding the portions of the shaft positioned therein from rotation, the abutting faces of these members being interlocked, as shown at 36; and carried by the members 29, 34 are suitable dies 37.

Intermediate these holding members 29, and mounted upon the bed of the machine, preferably supported by rollers 38 (see particularly Figs. 15 and 16), are members 39 constituting portions of twisters. In the present exemplification of this invention, three of these members 39 are shown, and the intermediate members 39 may be of a size to engage and clamp the double crank portions 31 of the shaft.

Mounted upon the slide 23 are twister members 40 which co-operate with the members 39, and these members 40 are rotatably mounted in any desired or suitable manner, such as by means of guides or tracks 41 (see particularly Figs. 13 and 17), which in turn are adjustably mounted upon the slide by means of fastening bolts or devices 42. These guides 41 receive flanges 43 on the members 40, so as to permit of rotation of the members 40 and, at the same time, hold the members in position with respect to the slide, to be raised and lowered with the slide. The members 40 on the slide co-operate with the respective members 39 supported by the bed, and when the slide is lowered to cause the members 42 to contact the respective members 39, suitable dies 44 which are carried by the respective members 39, 40, will grip another portion of the shaft 30. The twisters thus formed will, by reason of the aforesaid construction, be adapted for rotary movement with respect to the holding members 29, 34, and in order to cause the members 39, 40 to rotate together, the abutting faces of the members may be undercut, as at 45, to cause the two members of the twister to rotate together.

Any suitable means may be provided for rotating the twisters, but a simple and efficient means embodies actuator members 46, 47, one arranged adjacent the front and the other adjacent the rear of the press bed. These actuator members 46, 47 are pivotally mounted, by their ends, upon pivot pins 48, which align with the center line of the pins 43, and the pins 48 are mounted in suitable supporting brackets. Each of the actuator members 46, 47 is linked to two pistons 49, 50 which respectively operate in cylinders 51, 52 (see particularly Figs. 2 and 6), the cylinders 51 being pivotally mounted upon the bed, as at 53, while the cylinders 52 are pivotally mounted on the bed, as at 54.

Fluid pressure is supplied to the cylinders 52 beneath the pistons therein, by means of a supply pipe 55, to raise the pistons and thereby swing the respective actuator members 46, 47 about their pivots to cause the twister members that are attached thereto to rotate in one direction, those which are connected to the actuator member 46 at the front of the machine (in a manner

to be described) rotating in the opposite direction from the twister members which are connected to the actuator member 47 at the back of the machine. This rotation will be imparted to the twister members when the slide is down and when the co-operating members of the twisters are in contact with each other.

After the shaft has been twisted (in a manner to be described), and when the slide is raised to separate the twisting members and also to separate the holding members, fluid pressure will be admitted into the cylinders 51 at the top of the pistons, to move them downwardly and thereby rotate the attached members of the twisters in the opposite direction, or to their normal position. At the same time, fluid pressure will be exhausted from the cylinders 52. The twister members 39 which are connected to the actuator member 46 are adjustably secured thereto, as at 56, (see particularly Fig. 16) so that they may be adjusted lengthwise of the axis of the shaft and positioned in accordance with the cranks of the shaft, while the twister members 39 which are intermediate the end twister members, and which are operated by the actuator member 47 at the back of the machine, are secured to the latter.

The dies may be secured in position in the respective twister and holder members in any suitable manner, such as by means of fastening members 57 (see particularly Fig. 12) which are recessed in the faces of the respective members and project over the dies, being anchored by means of suitable anchor bolts or fastening devices 58 (see particularly Fig. 12).

Any suitable means may be provided for imparting a rotary motion to one of the twister members when the co-operating members thereof are not in engagement, and to that end there may be provided a plurality of cylinders 59, which are supported by the slide 23 and are adjustable with the twister members. One of these cylinders is preferably provided for each of the twister members, and operating in the respective cylinders is a piston which is connected with a piston rod 60, and these piston rods, in turn, each carries a rack member 61 reciprocable in a suitable guide-way 62 (see particularly Fig. 4). Each of the racks engages a series of teeth 63 on one of the members of each of the twisters, so that when fluid pressure is admitted to the cylinders 59 through a fluid pressure supply pipe 64, the piston will be moved in the cylinder, and the gear and rack connection 61—63 will rotate the twister members in one direction.

In the present form of the invention, the cylinder and piston mechanism is arranged so that two of the twister members will be rotated in one direction by moving the respective racks 61 forwardly from the position shown in Fig. 15, and one is arranged so as to rotate the twister members in the opposite direction, or from the position shown in Fig. 15. The operation of these racks 61 may be automatically controlled by means of an automatically operated valve mechanism 65, shown diagrammatically in Fig. 2, and which valve mechanism may be, in turn, actuated by means of a cam or projection 66 carried by the slide 23, so that when the slide reaches a predetermined position in the cycle of its operation, and as shown in Fig. 2, the valve mechanism 65 will be opened to admit fluid pressure from the supply line 67, and when the slide moves so that the valve 65 will shut off the source of supply of fluid pressure, the exhaust 68 will be opened to permit the racks 61 to be moved in the opposite

direction by the respective actuating members 46-47.

When the slide is lowered so as to move the clamp members of the twisters and holders into co-operative relation, the actuator members will be swung about their pivots by means of fluid pressure being admitted into the cylinders 52 (see Fig. 2), and as the upper twister member 40 will be rotated by the lower fluid pressure member under the influence of the actuators 46-47, and as the exhaust 68 of the cylinders 59 will be open, the rotation of the twister members will not be interfered with. This operation will occur when the slide is down and the shaft is being clamped.

After the forged shaft has been placed into the lower twisting members and the lower holding members, and the slide is lowered, this operation of the twisters will twist the crankshafts to their proper relative angular positions. Subsequently thereto, the slide is raised while the twisters are in their rotated positions, that is, in the positions shown in Figs. 15 and 16. That is, the two outer crank pins will have been twisted in one direction, while the intermediate twisters will twist their crank pins in the opposite direction, while the position of the central crank pins will remain unchanged. This will place the crank pins angularly in the desired positions around the bearing pins at the ends of the shaft, which have remained in perfect alinement. All of the dies will then be in a position which fits the twisted crankshaft, and, as before stated, by having them slightly undercut in the required places, the upper dies can be stripped off and the crank shaft lifted from the lower dies. At the instant when the actuator members reach the limit of their movement, the slide 23 will start its upstroke, while the upper and lower dies remain in their twisted positions.

In order to limit the movement of the actuator members 46-47, and consequently the degree of rotation of the twister members, pins or projections 69 (see particularly Figs. 1 and 7 to 9) are provided on the slide 23, which are adjustably secured to the slide, preferably by being screwed thereto, and are held in their adjusted position with respect to the slide by means of suitable nuts or collars 70. These pins are so positioned that they will be engaged by shouldered portions 71 on the respective actuator members 46-47 (see Figs. 7 and 8), and therefore will limit the degree of pivotal movement of the actuator members as well as the extent of rotation of the twisters. Therefore, in order to vary such degree of throw, the pins or projections 69 may be adjusted, and, by so doing, the extent of throw of the actuator members may be varied. Before the actuator members are moved about their pivots 48, the slide 23 will have descended and the holders and twisters will be closed, and the pins or projections 69 will be positioned with respect to the bed. After this operation the actuator members, swinging about their pivots, will be limited in their movements by the contact of the portions 71 of the actuator members with such pins or projections.

After the shaft has been twisted in the manner just described, and when the slide is raised so as to open the twisting and holding members, the shaft, in its completed shape, may be ejected from the lower twister and holder members. To accomplish this there is provided an ejector mechanism which may be of any suitable construction, but preferably embodies a bar or member 72 (see particularly Figs. 2, 13 and 14), which

is mounted within the bed of the press and has connected to it, preferably at the ends thereof, rods 73, on the ends of which rods are provided pistons 74 that operate in cylinders 75, the cylinders in turn being supported in any suitable manner, such as by means of supports 76 secured to the slide 23, so as to move with the slide. The bar or member 72 is of sufficient weight to cause the same to drop by gravity, moving the pistons 74 in the cylinders 75.

Spring operated catch members 77 are provided which project into the cylinders 75, and these catch members 77 have connected thereto pistons 78 operable in cylinders 79. The lower face of each of the catch members 77 is beveled, and the upper face of the piston 74 is also beveled, as at 80. The normal position of the bar or member 72 is such that the pistons 74 will be below the catch members 77 when the slide 23 is elevated, and before the operation of the press. When the slide 23 is lowered to close the holding and twisting members, and as the pistons 74 are at the lower end of the cylinders 75, as the cylinders are lowered with the slide, the beveled surface 80 of the pistons 74 will engage the beveled face of the catch members 77, so that the catch members will pass beneath the piston heads 74 as the pistons 74 move to the upper end of the cylinders 75. With the parts in this position, and when the slide 23 is raised, the bar or member 72 will remain in its lowered position by reason of gravity. However, when the slide 23 and the cylinders 75 are then raised, the catch members, being beneath the piston heads 74, will eventually engage under the piston heads, and before the slide 23 reaches the limit of its upward movement. When the catch members 77 do engage under the pistons 74, a further raising movement of the slide 23 will cause the bar or member 72 to be raised. This will also raise ejector pins 81 which rest thereon and which are provided with ejector heads 82, causing the latter to engage the shaft 30 and raise it from the lower open holding and twisting members, after which the shaft may be removed laterally from the machine in any suitable manner (not shown). A suitable pin 83 (see Fig. 14), which operates in a slot 84 in the ejector pins, may be provided to prevent the ejector pins from rotating.

After the shaft has been thus ejected, and in order to permit the bar or member 72 and the ejector pins to return to their normal positions by gravity, and independently with respect to the movement of the slide, pistons diagrammatically represented at 78 are provided. Fluid pressure is admitted into the cylinders 79 on one side of the pistons 78 through the supply pipes 85, and operates upon the pistons and moves them backwardly against the stress of their holding springs, together with the pistons. The catch members 77 will then be moved out of engagement with the pistons 74, thereby allowing the bar or member 72 to drop by gravity. This unlocking means for the ejector bar or member 72 is preferably controlled by means of a suitable manual control 86 which may be of any desired construction, such as an ordinary hand-operated valve, and as shown diagrammatically in Fig. 2 of the drawings. It is thought that the operation of this twisting mechanism will be clearly understood from the foregoing specification, but, briefly stated, it is as follows:

One member of each of the twisters is connected to one of the actuator members in such a manner that the actuator member in front of the press will rotate its respective twister mem-

bers in one direction, while the actuator member in the back of the press will rotate its twister member in the opposite direction. The members of the twisters and holders are so constructed that the rotation of the respective lower members will rotate the upper members when they are closed, and during the operation of twisting the cranks on the shaft. When, however, the slide is raised and the twister and holder members are separated so as to permit ejection of the shaft, such operation will be performed when the twisters are in their twisting position, that is, the position which they assume after the cranks have been twisted or formed. However, after the ejection, the lower members of the 15 twisters are rotated back to their normal positions, so that they will be horizontal, and the upper twister members, through the medium of the rack and gear construction, will be rotated back to their normal or horizontal positions, so that when the slide is lowered after a new shaft has been placed in the lower members of the twisters and holders, the upper twister and holder members will move into co-operating relation with the respective lower members to clamp the shaft. The twister members will then be rotated in the manner already described.

With this construction, it will be manifest that as the pressure requirements upon the twisting cylinders 52 and 54 increase, the pressure upon the clamping or holding cylinders will also be increased automatically. It will also be manifest that the ejecting mechanism will normally be inactive, and that during the cycle of operation of the machine, and when the slide reaches a predetermined point in the cycle of its return movement, the ejecting mechanism will be automatically locked to the slide, to be rendered active thereby. Thereafter, the ejecting mechanism may be released and rendered inoperative so as to be returned to its normal inactive position by gravity, at the will of the operator.

While the preferred form of the invention has been herein shown and described, it is to be understood that various changes may be made in the details of construction and in the combination and arrangement of the several parts, within the scope of the claims, without departing from the spirit of this invention.

What is claimed as new is:

1. A crankshaft twisting machine embodying separable pairs of co-operating holding members and twisting members, the members of each pair being entirely separate from each other, means common to one of the members of each pair for supporting all of the last said members separately from the respective co-operating members, and for bodily opening and closing movements away from and towards the respective co-operating members, means operable upon one of the members of the twisting pair for rotating both of them when they are closed, positive means operable upon the other of the twisting members to rotate it in the opposite direction when the twisting members are separated, and means for ejecting the shaft when the respective co-operating holding and twisting members are separated.

2. A crankshaft twisting machine embodying separable pairs of co-operating holding members and twisting members, means common to one of the members of each pair for opening and closing them, means operable upon one of the members of the twisting pair for rotating both of them when they are closed, means operable upon the other of the twisting members to rotate it in the

opposite direction when the twisting members are separated, ejecting means for ejecting the shaft when the respective co-operating holding and twisting members are separated, and means responsive to the operation of the first recited means for rendering the said ejecting means active at a predetermined time in the cycle of operation of the first said means.

3. A crankshaft twisting machine embodying 10 separable pairs of co-operating holding members and twisting members, means common to one of the members of each pair for opening and closing them, means operable upon one of the members of the twisting pair for rotating both of them when they are closed, means operable upon the other of the twisting members to rotate it in the opposite direction when the twisting members are separated, ejecting means for ejecting the shaft when the respective co-operating holding and twisting members are separated, means responsive to the operation of the first recited means for rendering the said ejecting means active at a predetermined time in the cycle of operation of the first said means, and means operable at will for releasing the said ejecting means, whereby the latter will be rendered inactive.

4. A crankshaft twisting machine embodying a plurality of separable pairs of co-operating holding members and a plurality of pairs of twisting members, the members of each pair being entirely separate from each other, means common to one of the members of each pair for supporting all of the last said members separately from the respective co-operating members, and for bodily opening and closing movements away from and towards the respective co-operating members, means operable upon one of the members of each of the twisting pairs for rotating both members of each pair when they are closed, means individual to and operable upon the other of each of the twisting members to rotate the respective members in the opposite direction when the twisting members are separated, and means for ejecting the shaft when the holding and twisting members are separated.

5. A crankshaft twisting machine embodying a plurality of separable pairs of co-operating holding members and a plurality of pairs of twisting members, the members of each pair being entirely separate from each other, means common to one of the members of each pair for supporting all of the last said members separately from the respective co-operating members, and for bodily opening and closing movements away from and towards the respective co-operating members, means operable upon one of the members of each of the twisting pairs for rotating both members of each pair when they are closed, means individual to and operable upon the other of each of the twisting members to rotate the respective members in the opposite direction when the twisting members are separated, and means for ejecting the shaft when the holding and twisting members are separated; one of said pairs of twisting members being rotatable in the opposite direction with respect to another of said pairs.

6. A crankshaft twisting machine embodying a plurality of separable pairs of co-operating holding members and a plurality of pairs of twisting members, the members of each pair being entirely separate from each other, means common to one of the members of each pair for supporting all of the last said members separately from the re-

spective co-operating members, and for bodily opening and closing movements away from and towards the respective co-operating members, means operable upon one of the members of each of the twisting pairs for rotating both members of each pair when they are closed, means individual to and operable upon the other of each of the twisting members to rotate the respective members in the opposite direction when the twisting members are separated, means for ejecting the shaft when the holding and twisting members are separated, and fluid pressure actuated means for controlling the operation of said holding and twisting members.

7. A crankshaft twisting machine embodying 15 separable pairs of holding members and twisting members, the members of each pair being entirely separate from each other, means common to one of the members of each pair for supporting all of the last said members separately 20 from the respective co-operating members, and for bodily opening and closing movements away from and towards the respective co-operating members, means operable upon one of the members of the twisting pair for rotating both members of the pair when they are closed, positive means individual to and operable upon the other member of the respective pairs of twisting members to rotate them in the opposite direction when the members are separated, means mounting the 30 twisting members for lateral adjustment, and ejecting means for ejecting the shaft from the holding and twisting members when they are respectively separated.

8. A crankshaft twisting machine embodying 35 separable pairs of holding members and twisting members, means common to one of the members of the pairs of twisting members for opening and closing them, means operable upon one of the members of the twisting pair for rotating 40 both members of the pair when they are closed, means embodying gear and rack mechanism operable upon the other member of the respective pairs of twisting members to rotate them in the opposite direction when the twisting members are 45 separated, fluid pressure means for controlling the operation of the gear and rack mechanism, means mounting the twisting members for lateral adjustment, and ejecting means for ejecting the shaft from the holding and twisting members when they are respectively separated.

9. A shaft twisting machine embodying pairs of co-operating holding members and twisting members, a slide upon which one member of each pair is mounted, means for actuating the slide 55 to bring the said members mounted thereon into co-operating relation with the other members of the respective pairs, a pivotally mounted actuating member connected with one of the members of the twisting pairs, fluid actuated means for swinging the said actuating member about its pivot to rotate both of the members of the twisting pairs when they are in contact with each other, means individual to one member of each pair of twisting members to rotate them in the 60 opposite direction when the members of the pairs are separated, means for ejecting the shaft when the pairs of members are separated, means for moving said actuating member about its pivot in the opposite direction, and spaced stops for 65 limiting the extent of rotation of said twisting members in both directions, one of said stops being carried by said slide.

10. A crankshaft twisting machine embodying pairs of co-operating holding and twisting mem-

bers, a slide upon which one member of each pair of twisting members is rotatably mounted, means for actuating the slide to bring the members thereon into co-operating relation with the other members of the respective pairs, a pivotally mounted actuating member, fluid pressure means for operating said actuating member to rotate the co-operating members of the twisters when they are closed, fluid pressure means individual to the twister members that are on the slide for rotating them when the twister members are separated, fluid pressure means for rotating the other of the twister members in the opposite direction when the twister members are separated, means for ejecting the shaft when all of said co-operating holding and co-operating twisting members are separated, and means for automatically controlling the operation of all of the said fluid pressure means.

11. A crankshaft twisting machine embodying pairs of co-operating holding and twisting members, a slide upon which one member of each pair of twisting members is rotatably mounted, means for actuating the slide to bring the members thereon into co-operating relation with the other members of the respective pairs, a pivotally mounted actuating member, fluid pressure means for operating said actuating member to rotate the co-operating members of the twisters when they are closed, fluid pressure means individual to the twister members that are on the slide for rotating them when the twister members are separated, fluid pressure means for rotating the other of the twister members in the opposite direction when the twister members are separated, means for ejecting the shaft when all of said co-operating holding and co-operating twisting members are separated, means for automatically controlling the operation of all of the said fluid pressure means, and spaced stops one for limiting the rotation of the twister members in each direction, one of said stops being responsive to its movement into and out of operative position, to the movement of the said slide.

12. A shaft twisting machine embodying co-operating pairs of holding members and twisting members, a slide, one of the members of each of said pairs being movable with the slide into and out of operative relation with respect to the other co-operating member, means for rotating one of the twisting members of each pair when they are closed, to rotate the other member of the respective pairs, an ejector for ejecting the shaft when said holding and twisting members are open, means for actuating said ejector, the last said means embodying co-operating elements, one of which is connected to the slide and the other to the ejector, said elements being relatively movable during a predetermined portion of the movement of the slide, means operating, when the slide has reached a predetermined position in its movement, to automatically lock said elements together, whereby the slide will actuate the ejector, and means for unlocking said elements whereby the ejector will be free to move independently of the slide.

13. A shaft twisting machine embodying co-operating pairs of holding members and twisting members, a slide, one of the members of each of said pairs being movable with the slide into and out of operative relation with respect to the other co-operating member, means for rotating one of the twisting members of each pair when they are closed, to rotate the other member of the respective pairs, an ejector for ejecting the shaft when

11

said holding and twisting members are open, means for actuating said ejector, the last said means embodying co-operating elements, one of which is connected to the slide and the other to the ejector, said elements being relatively movable during a predetermined portion of the movement of the slide, means operating, when the slide has reached a predetermined position in its movement, to automatically lock said elements together, whereby the slide will actuate the ejector, means for unlocking said elements whereby the ejector will be adapted to move independently with respect to said slide, and fluid pressure means for imparting the last recited movement to the ejector.

14. A crankshaft twisting machine embodying a slide, separable pairs of holding and twisting members, means common to one of the members

12

of the pairs for opening and closing them, means embodying an actuator operable upon the twisting members, when they are closed, to rotate them in one direction, a stop carried by the slide and movable into position for limiting the rotation of the twisting members in the said direction and out of such position, said stop being adjustably mounted upon the slide, whereby the extent of rotation of the twisting members, when closed, may be varied at will, the second said means also operating to rotate one of the twister members of the pair in its opposite direction when the members of the pairs are open, and means for rotating the other members of the pairs of twisters in the opposite direction when the twisting members are open.
